CARL AUGUST LINDGREN AND WILLIAM HUDSON PERKINS, OF HATHORNE,
MASSACHUSETTS.

AUTOMATIC LAUNDRY-VALVE.

1,159,967.

Specification of Letters Patent.

Patented Nov. 9, 1915.

Application filed July 23, 1914. Serial No. 852,750.

To all whom it may concern:

Be it known that we, CARL A. LINDGREN and WILLIAM H. PERKINS, citizens of the United States, and residents of Hathorne, 5 in the county of Essex and State of Massachusetts, have invented a new and Improved Automatic Laundry-Valve, of which the following is a full, clear, and exact description.

This invention relates to the control of 10 water to a laundry machine or other device, and has particular reference to a simple, reliable and easily controlled mechanism for the purpose of delivering either hot or cold water or a mixture of hot and cold 15 water to a washing machine.

A further object of the invention is to provide means to automatically control the flow of water into the machine or the depth of water in the machine irrespective of the 20 temperature of the water.

A still further object of the invention is to provide an improved device to vary the depth at which the automatic action of the valves takes place.

25 The foregoing and many other objects of the invention will hereinafter be more fully described and claimed and illustrated in the drawings forming a part of this specification in which like characters of reference 30 indicate corresponding parts in all the views, and in which—

Figure 1 is a side elevation of a preferred embodiment of the invention, certain parts being broken away; Fig. 2 is a front elevation 35 of the same; Fig. 3 is a vertical transverse section on the line 3—3 of Fig. 1; Fig. 4 is a horizontal longitudinal section substantially on the line 4—4 of Fig. 1, and indicating the valve in open position and set 40 to deliver both hot and cold water; Fig. 5 is a view similar to Fig. 4, but indicating the valve closed; Fig. 6 is a longitudinal sectional detail of the main valve mechanism on the line 6—6 of Fig. 5; Figs. 7 and 8 are 45 side elevations of details of the pilot valve; Fig. 9 is a sectional view of the pilot valve on the line 9—9 of Fig. 8; Fig. 10 is an inner end view of the conical valve plug shown in Fig. 6 in detail; Fig. 11 is a vertical transverse section of the valve casing substantially on the line 11—11 of Fig. 1; Fig. 12 is a longitudinal section of the same 50 on the line 12—12 of Fig. 5; and Fig. 13 is an elevational view indicating the relation of

the valve mechanism to the washing machine 55 and adaptation of the automatic float mechanism thereto.

The several parts of the device may be made of any suitable materials, and the relative sizes and proportions, as well as 60 the general design of the mechanism, may be varied to a considerable extent without departing from the spirit of the invention hereinafter more fully set forth and specifically claimed. 65

Referring more particularly to the drawings we show at 15 a washing machine of any suitable type or construction, and 16 indicates a pipe adapted to deliver water into the lower portion of the machine. At 70 17 is provided a float chamber having a pipe 18 communicating with the bottom of the machine. This pipe is fitted with a normally open stop cock 19, the same, however, being adapted to be closed when the automatic operation of the valve is desired to be prevented, as when the machine is to be left empty. 75

The numeral 20 indicates as a whole our improved valve mechanism. This mechanism includes a casing 21 of novel and peculiar construction, the same being substantially cylindrical longitudinally and including a plurality of chambers. Hot water is adapted to be admitted into the chamber 22 80 85 preferably at one side of the middle portion of the casing, and cold water is adapted to be admitted into the chamber 23 preferably diametrically opposite from the chamber 22, the hot and cold water being delivered to 90 the casing by means of pipes 22' and 23' respectively.

At 24 is shown a cylindrical valve seat lying between the hot and cold water chambers 22 and 23. This valve seat 24 is rigidly 95 supported substantially along the longitudinal center of the casing 21 and may, if desired, be cast integral therewith. By reference to Fig. 12 it will be noted that this cylindrical valve seat has open ends, the 100 rear end communicating directly with a delivery chamber 25 at the rear end of the casing and this in turn communicates through a port 26 with the discharge chamber 27 at the bottom of the casing and to 105 which the aforesaid pipe 16 is connected.

The numeral 28 indicates a cylindrical valve fitted in the seat 24 and adapted for

both reciprocation and rotation therein. The valve 28 has a pair of ports 22^a arranged circumferentially of the valve and adapted to register with a port 22^b of the hot water chamber and whereby the hot water may pass into the interior of the valve 28 and thence through end passageways 29 to the discharge chamber 25 (see Figs. 4 and 6). Likewise the valve 28 is provided with circumferentially arranged ports 23^a adapted to communicate with a port 23^b whereby cold water may pass from the chamber 23 into and rearwardly through the valve, taking the same course as above described in connection with the hot water, this condition allowing a mixture of hot and cold water to pass through the valve when the valve is set in mid position as to rotation, as shown in Figs. 4 and 5. More definitely stated, the valve 28 is adapted to rotate through an arc of substantially 180 degrees or 90 degrees in either direction from said mid position. One of the ports of each pair of circumferentially arranged ports leading through the wall of the valve 28 is adapted to maintain registry or communication with its corresponding valve seat port when the valve is rotated to the maximum extent, the other valve seat port at such time being closed by the imperforate portion 30 of the valve.

The means we provide to control the rotation of the valve 28 includes a valve stem 31 shown in Fig. 3 as polygonal in cross section and loosely fitted in a socket 32 of a closed head 33 at the front end of the valve 28. Said stem 31 extends forwardly, a cap 34 closing the front end of the casing 21 where it is fitted with a stuffing box 35 making it substantially watertight. A handle 36 is secured rigidly to the front end of the stem which cooperates with a yoke 37 shown conveniently clamped to or supported upon a neck 38 constituting a portion of the gland 35. This yoke has stops 37' and 37'' to determine the position of the handle 36 with respect to the delivery of hot and cold water respectively. The operator obviously may rotate the valve stem and valve at any time in either direction according to the character of water desired. If hot water only is desired, a rotation of the handle 36 to the left in Fig. 2 will cause the uppermost port 22^a to register with the port 22^b while the port 23^b will be closed. Movement of the handle in the extreme opposite direction will open the cold water port to the exclusion of the hot water.

Our devices for providing for the automatic control of the flow of water through the valve casing, irrespective of the temperature of the water delivered thereto, include a power piston 39 secured rigidly to the head 33 of the valve 28. This piston cooperates with the cylindrical front portion

or chamber 40 of the casing 21, means being provided of any suitable nature to control the action of the piston automatically by means of the pressure incident to the water supply; in this instance shown as provided through the cold water chamber 23. When the water pressure is exerted on the front face of the piston 39, it and the valve 28 will be forced rearwardly into the position shown in Fig. 4. When, however, the pressure is exerted against the rear face of the piston, the valve 28 will be closed as shown in Fig. 5, all of the valve ports being closed by the unbroken portions of the valve seat 24 and the end of the valve seat being sealed by a gasket 41 carried by a valve 42 rigidly secured at the rear end of a central support 43 extending longitudinally of the valve rearwardly from the head 33, said gasket 41 seating snugly against the rear end 44 of the valve seat 24. As shown in Figs. 5 and 10, the end valve 42 is provided with a lug 45 adapted to cooperate with a rib 46 to facilitate the assemblage of the valve parts.

Any suitable means may be provided to operate the piston 39 automatically in either direction. As a preferred means for this purpose we show a pilot valve located adjacent one side of the cylinder 40. The pilot valve structure comprises a valve plug 47 having a tapered fit in a seat 48 formed in the casing 21, the plug being held in fixed position by means of a cap 49 tapped into the front end of the seat 48, as shown best in Fig. 5. Referring to Figs. 5 and 7, the plug 47 has a cut-out 50 at the middle of its lower end and is hollow from its rear end forwardly to the head 51. The plug is formed with a circumferential groove 52 just at the rear of the head 51 and is provided with a series of ports 53 providing communication between the grooves 52 and the hollow interior. Likewise at the rear end another groove 54 is provided, and a series of ports 55 lead therefrom to the hollow interior. The interior of the plug and the seat 48 are always in communication through a port 56 with the cold water chamber 23, and the power cylinder 40 is always in communication through ports 52' and 54' 115 with the aforesaid grooves 52 and 54 respectively.

The pilot valve 57 is provided with heads 58 and 59 and an intermediate shank 60. The shank is bored all the way through the head 59, the bore 61 terminating adjacent the head 58. The head 58 is provided with a cavity 62 and ports 63 lead therefrom into an annular groove 64 in communication with the ports 55 when the valve 57 is in its rearward position, as shown in Fig. 4. Just in front of the groove 64 is a valve member 65 of slightly smaller diameter than the head 58 and adapted to seat upon the annular shoulder 66 when the pilot valve is in its 130

front position, as shown in Fig. 5. A series of holes 67 lead through the shank of the valve 57 just in front of the valve member 65 into the central bore 61 whereby communication may be had from the chamber 23 with the cylinder 40 on the front side of the piston 39 through the port 56, socket 48, cavity 62, ports 64 and 67, bore 61 and ports 53 and 52', when the valve is in its rear position shown in Fig. 4. The pressure of the water may act upon both faces of the piston 39, but such pressure is greater on the front face than on the rear face because of the greater amount of exposed surface. Hence, when the valve 57 is in the position just described, the pressure of the water will cause the piston to move rearwardly, opening the valve ports and allowing the water to flow from one or the other or both of the water supply pipes 22' and 23', as previously described. Any water which may be in the cylinder 40 back of the piston 39 when this movement takes place may pass freely therefrom through the port 54'. The means we prefer to use to move the valve 57 rearwardly automatically so as to initiate the delivery of water through the main valve casing includes a yoke 68 secured to a rock shaft 69 journaled in a bearing 70 and extending laterally from the main casing. The yoke 68 embraces the shank 60 of the pilot valve and when the rock shaft 69 is oscillated in either direction the valve is caused to reciprocate correspondingly. A bracket 71 is connected to the outer end of the rock shaft and has pivoted to its rear end a sleeve 72 through which a rod 73 extends loosely vertically. A cap 74 is fixed to the upper end of the rod 73 and serves by engagement with the upper end of the sleeve 72 to cause the rotation of the rock shaft 69 in a clockwise direction, as viewed in Fig. 1, when the rod 73 is drawn downwardly through the sleeve. A float 75 is connected to the lower end of the rod 73 and is adapted to operate in the chamber 17. When the water is low in the tank 15, the same level being observed normally in the chamber 17, the float 75 acting through gravity will descend, causing the movement of the bracket 71 and pilot valve mechanism as above described, and hence causing the flow of water to take place through the main valve whenever the level of the water in the tank or machine 15 drops to a certain predetermined point. When, however, the water rises in the machine and chamber 17 the float 75 will be buoyed upwardly, causing the rod 73 to move upwardly through the sleeve 72 until some part of the rod or a member attached thereto engages the sleeve 72 and causes rotation of the rock shaft and bracket in a counterclockwise direction and causing the pilot valve 57 to be thrown forwardly, as shown in Fig. 5.

When this action takes place at the pilot valve, the valve member 65 will seat against the valve shoulder 66 and close the communication forwardly through the plug 47. The water pressure through the pilot valve will then all be exerted through the ports 55, groove 54, port 54', so as to act directly upon the rear face of the piston 39 with the effect that the main valve 28 will be forced forwardly and closed, as shown in Fig. 5. This action is automatic and independent of the rotary position of the valve 28. The water which may be in the cylinder 40 in front of the piston 39 prior to this closing action may escape through the port 52', groove 52, ports 53 and an annular groove 76 around the head 59 and through the longitudinal grooves 77 extending rearwardly from the groove 76 along the head 59 into the hollow portion of the plug 47 through the chamber 48 and out through a small port 78 at the bottom of the casing 21 and into the bottom chamber 27 leading to the main discharge pipe. We have found by a number of experiments that the peculiar form of the pilot valve 57 with respect to the circumferential and longitudinal grooves prevents noise due to hammering or the like.

As a convenient means to set the automatic mechanism for operation at any desired depth of water in the machine 15, we provide a scale 79 upon the rod 72 having any suitable graduations thereon increasing in value downwardly. The illustration given indicates marks for inches from eight to seventeen. A bar 80 is arranged parallel to the rod 73 and gage 79 and at its lower end has a loop 81 surrounding the gage serving as a pointer or index in coöperation with the gage numbers. At the upper end of the bar 80 is a head 82 which is adapted to engage directly against the lower end of the sleeve 72, and the head includes a clamping device 83 of any suitable means adapted to grip the bar 73 in accordance with the desired position of the indicator 81 on the rod 79. As shown in Fig. 1, the indicator is set for a depth of sixteen inches. When the float 75 is lifted by water to the depth of sixteen inches, the head 82 will act upon the sleeve 72 and stop the flow. The minimum depth provided for, as indicated, is about seven inches, the index 81 being adapted to be limited in its upward movement along the scale by means of a stud 84. Under ordinary circumstances a lower level of water would never be desired for practical use of the machine. A downward movement of the bar 80 is limited by engagement of the head 82 against the upper end of the scale 79. If it is desired to empty the machine, the stop cock 19 is closed so as to prevent the weight of the float 75 from opening the main valve of the machine.

Having thus described our invention, we

claim as new and desire to secure by Letters Patent:—

1. In an automatic laundry valve, the combination with a main valve casing and a combined rotary and a longitudinally movable valve therein for delivering water either hot or cold, of automatically controlled pilot valve mechanism comprising a valve seat, a tapered valve plug fitted in said seat, means to lock said plug in position, said plug having a cut-out portion intermediate its ends on one side and having a closed head at its front end, said plug furthermore being hollow longitudinally from its rear end to said head, a pair of ports in the casing, said plug being formed with annular grooves adjacent each end and communicating with said ports; there being also ports formed through the plug leading through the grooves to said hollow interior, there being a valve seat formed within the plug between the rear end and said cut-out, and a reciprocating pilot valve mounted within the plug and bearing against said valve seat in one position, said valve having a hollow shank between the valve proper and the front end thereof, the pilot valve being formed with a groove surrounding its rear end, the rear end also being hollow and having a series of ports leading therefrom to said groove, substantially as set forth.

2. The combination with a main valve casing including a power cylinder and a recip-

rocating piston therein, said casing having a pair of ports communicating with opposite ends of said cylinder and being formed with a valve seat adjacent thereto and also having a port communicating with the end of said valve seat, of a plug fitted in said seat, said plug having annular grooves communicating with said pair of ports, the rear end of the plug being hollow and having ports leading from the hollow interior to both of said grooves, the hollow interior of the plug being also in communication with the third mentioned port whereby fluid pressure may always be communicated to the cylinder at either end of the piston, and a reciprocating pilot valve to control the direction of movement of said pressure fluid, said pilot valve having a valve head at its rear end, said head having a circumferential groove surrounding the same and a hollow interior communicating with the last mentioned groove through the ports, the other end of the pilot valve constituting a hollow shank having radial ports extending to the surface thereof in front of the valve head, substantially as set forth.

In testimony whereof we have signed our names to this specification in the presence of two subscribing witnesses.

CARL AUGUST LINDGREN.

WILLIAM HUDSON PERKINS.
